UNITED STATES PATENT OFFICE.

OTTO W. WILDE, OF WICHITA, KANSAS.

COMBINED WHIP, REIN, AND LAP-ROBE LOCK FOR VEHICLES.

1,079,530.

Specification of Letters Patent.

Patented Nov. 25, 1913.

Application filed February 28, 1913. Serial No. 751,345.

To all whom it may concern:

Be it known that I, OTTO W. WILDE, a citizen of the United States, residing at Wichita, in the county of Sedgwick and 5 State of Kansas, have invented certain new and useful Improvements in Combined Whip, Rein, and Lap-Robe Locks for Vehicles; and I do declare the following to be a full, clear, and exact description of the invention, such as will enable others skilled 10 in the art to which it appertains to make and use the same.

This invention relates to carriages and wagons, and more especially to whip sockets 15 such as are provided with a lock; and the object of the same is to produce a combined whip, rein, and lap robe lock possessing certain characteristic features of improvement over my former patents numbered 877,623 20 issued January 28, 1908, and 944,530 issued December 28, 1909. These objects are accomplished by carrying out the invention in the manner hereinafter more fully described and claimed, and as shown in the 25 drawings wherein—

Figure 1 is an elevation of this device, viewed from the inside of the buggy with part of its dashboard broken away; and Fig. 2 is a horizontal section on the line 30 2—2 of Fig. 1, while Fig. 3 is a cross section on the line 3—3 thereof. Fig. 4 is a perspective detail of the whip socket removed from the casing; Fig. 5 is a plan view of the casing and a cross section of 35 that portion of the dashboard to which the casing is attached. Fig. 6 is a vertical section through the device just in rear of the dashboard, showing the parts within the casing standing in the position they assume 40 when all elements are locked in place; and Fig. 7 is a similar view of the casing and the lower end of the locking device, showing the parts in full lines in the position they assume after they have been 45 moved to free the whip-lock, and in dotted lines in the position they assume after they have been moved to free the locking devices for the robe and the reins. Fig. 8 is a cross section on the line 8—8 of Fig. 6. Fig. 9 is a perspective detail of the locking device 50 detached.

The base member 1 comprises top and bottom horizontal bars 2 and 3 connected by U-shaped clips or brackets 4 which may 55 have hooks 5 for engaging the dashboard of

the vehicle or may be attached to said dashboard or to the wagon box in any suitable manner, and an intermediate clip or bracket 6 carrying a spring 7 as shown. The robe lock consists of a bar 8 pivoted at 9 in one 60 end of the base and having upright pins 10 through its body adapted to engage the robe when the latter is folded around this bar and the whole pressed backward against the tension of the spring 7. The rein holder is 65 another upright pin 11 near the free end of said bar 8 and over which the reins are led when they are to be locked in this device, although ordinarily this may not be necessary. The free end of the bar 8 has a foot 70 piece 12 by means of which it may be pressed to the rear against the tension of its spring 7, and opposite said foot piece it has an eye 13 adapted to pass between eyes 14 in a guide 15 carried by the corresponding 75 end of the base 1 when said bar 8 is pressed thereinto; so that the locking bolt may descend through the alined eyes to hold this bar in place.

Upstanding from the base at a point adjacent the guide 15 is an ear 16 to which is secured the tubular casing 17 which carries the whip socket and lock and whose details of construction form the subject matter of the present improvement. This casing may have a collar 18 at its upper end containing a soft flange 19 through which the butt of the whip may be passed, and by preference this end has a stud 20 with a screw 21 projecting therefrom to receive washers 22 and 23 which may stand inside and outside of the dashboard, and also to receive a nut 24 to steady the upper end of the casing when it is attached to the vehicle in this manner. At a suitable point the casing is provided 90 internally with a lock designated by the numeral 25, its bolt 26 capable of being shot by turning a key or otherwise.

The whip socket, best seen in Fig. 4, comprises a hollow casting 30 preferably having a pair of rings 31 by means of which it is fitted closely within the casing 17, and a boss 32 to be engaged by a screw or other device 33 passed through the casing and into such boss as shown, and the rings have upright 100 notches 34 at one side and upright notches 35 at the other side of the device for a purpose yet to appear. The numeral 36 designates an internally threaded boss disposed between two of the last-named notches 35, and 105

37 is a set screw engaging this boss and having a slot 38 through its body adapted to be brought into line with the notches 35 when the head of the set screw stands upright. 5 The inner end of the set screw has a button 37' on which is swiveled one leaf 39 of an inverted V-shaped spring whose other leaf 39' stands within the interior of the casting and is adapted to be clamped against the 10 handle of the whip H above the knob K which usually occurs at the extreme end thereof. It follows that by turning the set screw inward the spring is pushed toward the whip-handle until the latter is clamped 15 within the socket, and yet the spring serves to prevent wear on the whip-handle by the rotating button at the inner end of the screw; when the latter is rotated in the opposite direction, the spring is retracted 20 from the whip-handle, and the outer leaf of the spring then serves to prevent the complete withdrawal of the thumb screw. During its rotation the slot in this thumb screw comes opposite the notch or groove 35 25 in this side of the casting, twice for each revolution of the thumb screw, and therefore if a bolt were projected through the groove and through its slot 38 the thumb screw would be locked or prevented from 30 further rotation.

The locking member, best seen in detail in Fig. 9, comprises two bolts and a connection between them. One of these bolts 40 has a slot 41 in its body which moves over the key 35 hole and a finger 42 at its upper end adapted to be engaged by the bolt of the lock, while its lower end is reduced into a finger 43 which travels in the vertical notches 35 in the casting and is adapted to be projected 40 through the slot 38 in the shank of the thumb screw as described below. Another bolt 46 is connected with the bolt 40 by means of a ring 47 which fits loosely within the casing 17, the connection between this ring 47 and the long bolt 46 being by means of a stud 49 projecting through an upright slot 50 in the side wall of the casing and within easy reach of the operator for a purpose to be described below. 45

50 The long bolt 46 has a notch 48 cut into it near its lower end, which end moves through the alined eyes in the guide 15 described above. Within the casing above the upright slot is disposed a stop 52 so located with 55 respect to the length of the slot 50, the position of the lock, and the position of the eye 13 of the locking bar 8, that the action of parts will be as follows. By preference I would make this device entirely of metal, 60 suitably ornamented so as to be tasteful in appearance and suitably treated so that it will be weather proof. While I have shown a lock which is operated by means of a key, it is of course possible to use a permutation lock, although the advantage of using

a key as described below will then be lost sight of.

The lap robe is attached to the bar 8 by passing it around the same and over the pins 10 in a manner well understood, and the reins are similarly attached by passing them around the pin 11; but either or both of these devices may be used with or without the fastening means for the whip. Ordinarily the whip handle H is dropped through the soft ring 19 into the whip socket wherein the spring prevents it from rattling. To lock it in place the screw 37 is set up so that the leaves of the spring are compressed and the innermost leaf 39' is borne against the handle H above its knob K, care being taken to stop the rotation of the set screw at a point where its slot 38 stands upright. The locking member is moved downward by depressing the stud 49 within the slot 50, and this projects the long bolt 46 through the alined eyes 14 and 13 and locks the bar 8 in position, and simultaneously projects the lowermost finger 43 of the short bolt 40 through the slot 38 in the set screw and locks the latter against rotation. In the act of unlocking the device, if the long bolt be provided with a notch 48 it will be necessary to press the foot piece 12 to the rear to disengage the eye 13 from said notch before this bolt is raised; but said notch may be omitted. In any event, when the lock is operated its bolt disengages the upper finger 42 of the short bolt, after which the entire locking device can be raised by lifting its stud 49 in the slot 50; but the upward movement thereof is limited by the stop 52 against which the upper end of the long bolt strikes at a time when the lower finger of the short bolt has disengaged the set screw so that the latter can be turned to release the whip. In order to raise the locking bolt still higher, it is only necessary to press the stud 49 inward 100 so that the upper end of the long bolt passes the stop 52 and the stud may be lifted to the extreme upper end of the slot 50, when the lower end of this bolt will clear the eye 13 in the bar 8, and the latter can be 105 swung open to disengage the robe and the reins. Thus it will be seen that by providing the stop 52 the locking member has a restricted and an expanded path of movement upward—its restricted movement being sufficient to free the whip which the user will probably desire frequently to withdraw from its socket, and its expanded movement being sufficient to free the lap robe which the user will no doubt not often 110 care to remove. The reins, if attached to this device at all, will be engaged with the pin 11 in such manner that they will have considerable looseness so that he can 115 drive the horse while the reins are fastened 120

on the pin, and hence the only time he would care to disconnect the reins entirely would be when he would be unhitching the horse.

5 Thus it will be seen that my device permits the selective use of parts for locking the whip, reins, and lap robe, or any two of them, or all of them, and disengaging them from the lock individually or collectively as desired.

What is claimed as new is:

1. A lap robe lock including a guide having alined eyes, and a movable robe-holding bar having an eye adapted to be passed between those of the guide; combined with an upright casing having an upright slot and a stop on its interior above said slot, a bolt movable vertically within said casing behind the slot and having a stud projecting through the latter, its upper end adapted to strike said stop and its lower end adapted to be projected through the alined eyes of the guide, and whip-locking mechanism connected with said bolt but thrown out of action when the latter is raised.

2. A lap robe lock including a guide having alined eyes, and a movable robe-holding bar having an eye adapted to be passed between those of the guide; combined with an upright casing having an upright slot and a stop on its interior above said slot, a bolt movable vertically within said casing behind the slot and having a stud projecting through the latter, its upper end adapted to strike said stop and its lower end adapted to be projected through the alined eyes of the guide, a whip socket, means for holding the whip-handle therein, and locking mechanism for said holding means connected with said bolt but adapted to be thrown out of action when the latter is raised.

3. A lap robe lock including a guide having alined eyes, and a movable robe-holding bar adapted to be passed between the eyes of the guide; combined with an upright casing having an upright slot and a stop on its interior above said slot, a bolt movable vertically within said casing behind the slot and having a stud projecting through the latter, its upper end adapted to strike said stop and its lower end adapted to be projected through the alined eyes of the guide, a whip socket, means for holding the whip-handle therein, a set screw for advancing said holding means, the shank of the set screw having a transverse slot, a bolt connected with said first-named bolt and having a finger adapted to be projected through said slot as both bolts are depressed and to be raised out of said slot as the first-named bolt is raised until its upper end engages said stop, and means for locking both bolts in depressed condition.

65 4. In a device of the class described, the

combination with a tubular casing having a threaded boss in one side and an upright slot in the other, a lock carried by the casing, a whip socket in the latter, holding means for the whip, a set screw in said boss engaging said means and having a slotted shank, and a locking member including a finger adapted to be passed through said slot in the shank of the set screw, a stud projecting through the slot in said casing, and a long bolt depending below the casing and having a notch in its edge; of a lap robe holder including a guide having alined and spaced eyes, a base, and a spring-pressed bar pivoted in the base and having an eye adapted to be passed into said guide and to stand in line with the eyes therein to receive said bolt.

5. In a whip-socket lock, the combination with an upright casing, and a whip socket therein having surrounding rings pierced with upright alined notches and an internally threaded boss between said rings grooved in a line with said notches; of a set screw engaging said boss and having a slotted shank, a lock, and a bolt having a finger adapted to be projected through the slot of the set screw.

6. In a whip-socket lock, the combination with an upright casing, and a whip socket therein having surrounding rings pierced with upright alined notches and an internally threaded boss between said rings grooved in a line with said notches; of a set screw engaging said boss and having a slotted shank and a head at its inner end, an inverted V-shaped spring whose outer leaf is swiveled on said head and whose inner leaf engages the handle of the whip, a bolt having a finger adapted to be projected through the slot in the shank of the set screw, and means for locking said bolt.

7. In a whip-socket lock, the combination with an upright casing, and a whip socket therein having surrounding rings pierced with upright alined notches and an internally threaded boss between said rings grooved in a line with said notches; of a set screw engaging said boss and having a slotted shank, a lock within the casing above said boss, and a bolt having a slot in its body moving over the key-hole of said lock, a finger at its upper end adapted to be engaged by the lock-bolt, and a finger at its lower end adapted to be projected through the slot in the set screw, for the purpose set forth.

8. In a whip-socket lock, the combination with an upright casing, and a whip socket therein having an internally threaded boss grooved in an upright line; of a set screw engaging said boss and having an angular shank and a head at its inner end, an inverted V-shaped spring whose outer leaf is swiveled on said head and whose inner leaf engages the handle of the whip, a bolt mov-

able in said grooves and adapted to engage the shank of the set screw, and means for locking said bolt.

9. In a device of the class described, the combination with a tubular casing having a threaded boss in one side and an upright slot in the other, a lock carried by the casing, a whip socket in the latter, holding means for the whip, a set screw in said boss engaging said means and having a slotted shank, and a locking member including a finger adapted to be passed through said slot in the shank of the set screw, a stud projecting through the slot in said casing,

and a long bolt depending below the casing; 15 of a lap robe holder including a guide having alined and spaced eyes, a base, and a bar pivoted in the base and its free end adapted to be passed into and locked within said guide by the bolt when projected through 20 the eyes therein.

In testimony whereof I have hereunto set my hand in presence of two subscribing witnesses.

OTTO W. WILDE.
